KNITTING MACHINE

Henry Harold Holmes and Robert Harold Robinson, Leicester, England, assignors to Wildt and Company Limited, Leicester, England, a British company

Application May 25, 1934, Serial No. 727,540
In Great Britain May 27, 1933

7 Claims. (Cl. 66—134)

This invention consists in improvements in or relating to knitting machines and is an improvement in or a modification of the yarn-feeder mechanism described and claimed in prior application for United States Letters Patent Serial No. 562,898.

The present improvement or modification comprises in combination a yarn-feeder, an associated yarn-gripper and means to release the gripper only when the free end of the yarn presented by the yarn-feeder to the needles has been taken by one or more needles. Hitherto, it has been customary to release the gripper as the feeder is moved towards the feeding position from a non-feeding position; but it is now found that by releasing the yarn prior to the taking of the free end thereof by one or more needles the yarn is apt to float out too freely so that it cannot be fed with certainty, course by course, to a particular needle as, for example, when splicing. In utilizing the combined feeder and gripper for such a purpose it is necessary that the yarn shall always be taken by a particular needle and withdrawn at any other predetermined needle. By the present invention it is found that the yarn can, with more or less certainty, always be fed to and taken by the same needle so that commencement of knitting of the splicing thread course by course occurs always in the same wale. By the mechanism described in the prior specification the yarn can always be withdrawn also at a predetermined wale and consequently by the utilization of a similar withdrawing mechanism in the present invention the edges of the splice both at the beginning and at the end will show as cleanly defined lines in the fabric.

In a preferred form of the invention the gripper is movable relatively to the feeder in the general plane of movement of the latter and is combined with actuating means to control its movement relatively to the feeder at required times for the purpose of causing the yarn to be gripped or released as desired. Preferably, the yarn-gripper is combined with two rotatable spindles which are mechanically coupled to rotate simultaneously in opposite directions, means operatively connecting one of the spindles with the gripper whereby the latter will be moved relatively to the feeder, and actuating means to rotate the spindles in either direction at will.

In a specific form of the invention there is interposed between the gripper and the feeder a yielding yarn clamp which is yieldingly urged at all times towards the body of the feeder so that the yarn in passing between the latter and

the clamp is subjected continuously to a predetermined restraint to its free travel.

In order that the invention may be more clearly understood two preferred examples will now be described in detail with the aid of the accompanying drawings, in which—

Figure 1 is a plan of one form of feeder mechanism,

Figure 2 is an elevation thereof,

Figure 3 shows the mechanism as viewed from the right of Figure 2,

Figure 4 is a view similar to Figure 1 showing the gripper moved to the opposite extreme position relatively to the feeder from that shown in Figure 1,

Figure 5 is a plan similar to Figure 1 of a modified form of the invention,

Figure 6 is an elevation of the mechanism shown in Figure 5,

Figure 7 illustrates the mechanism of Figure 5 viewed from the right of that figure.

Figure 8 illustrates the action of the mechanism illustrated in Figures 1 to 4 at the commencement of a yarn-feeding operation.

Figure 9 diagrammatically illustrates the position of the needle taking the yarn in Figure 8 relatively to the stitch-cam.

Figure 10 is a view similar to Figure 8 at the moment of release of the gripper, and

Figure 11 is a view similar to Figure 9 showing the position of the first needle to take the yarn in relation to the stitch-cam.

Like reference numerals indicate like parts in the several figures of the drawings.

Turning first of all to Figures 1 to 4, 10 indicates the needle-cylinder, and 11 indicates the ring upon which the feeder mechanism is mounted. Secured to the ring is a bracket 12 having at each end slots 13 in which are received clamping nuts and bolts 14 whereby the bracket 12 is secured to the ring 11, the slots 13 permitting slight adjustment of the bracket circumferentially of the cylinder 10.

A feeder 15 pivotally mounted in the bracket 12 on a pin 16 is similar in its general design to the feeder described in prior United States specification Serial No. 562,898 and on a depending stub 17 there is mounted a locking plate 18 controlled by a spring 19 which serves to hold the feeder when it is desired in its inoperative position as described in the aforesaid prior specification. Reference may be made to the latter for a fuller understanding of the mounting and arrangement of the feeder 15 and the locking plate 18, and as these parts of themselves and

their arrangement and mounting do not constitute the present invention but are only elements therein it is thought unnecessary to describe them in further detail.

5 Instead of the freely pivoted gripper jaw 19 of the previous construction there is now provided a yielding clamp in the form of a spring plate 20 which is yieldingly urged at all times, by its own resilience, to engage the yarn which is led between it and the body of the forwardly-projecting nose of the feeder in its passage between the end feed-eye 21 and a more rearward guide-eye 22 through which the yarn passes from the under to the upper side of the nose of the feeder. In the drawings the yarn is indicated at 23. The clamping plate is secured in position by means of screws 24.

20 A movable abutment 25, hereinafter termed "a gripper" is mounted so as to be movable under control towards and away from the yarn-feeder in the general plane of movement of the latter so that when it is adjusted into the full-line position shown in Figure 2 it will press on to the clamp 20 to force the latter into close engagement with the yarn 23 and to prevent feeding of the latter so that continued relative rotation between the feeder and the needle-cylinder will impose a breaking stress on the yarn when desired. This abutment 25 takes the place of the 25 abutment 23 of the construction according to the earlier specification but unlike the abutment 23 the gripper 25 is positively moved to and fro relatively to the feeder. When moved into the chain-line position shown in Figure 2, clamp 20 is 30 released and only presses on to the yarn by its own resilience.

35 In an upward extension 26 of the bracket 12, there is formed a guide-way in which a slide 27 is received, the guide-way being indicated by dotted lines at 28. The horizontal portion of the gripper 25 is secured to the bracket extension 26 by screws 29 passing through slots in slide 27, a distance-piece 30 being formed on the outermost screw 29 to space apart the gripper and the slide 40 27. The slide projects at 31 to engage beneath the upper end of the inclined portion of the gripper 25 and the latter is held in position by screws 29 so that when the slide is moved towards the axis of the needle-cylinder the inclined part 45 will be moved away from the feeder; but when the latter is withdrawn away from the needle-cylinder the nose of the gripper will be left free to deflect slightly as it is pressed on to the clamp 20 owing to its own natural resilience.

50 55 In order to actuate the slide there are two spindles 32 and 33 mounted in the upwardly-extending portion 26 of the bracket 12. These spindles are parallel with one another and with the axis of the needle-cylinder and are interconnected by spur-gearing 34 at their upper ends. Secured to each spindle is an actuating arm, these 60 two arms being indicated at 35 and 36, whereof the arm 35 is secured to the spindle 32 and the arm 36 is secured to the spindle 33. The latter 65 are cranked downwardly so that their lower ends extend to a position at which they can be engaged by adjustable external abutments 37 and 38 (Figures 1 and 4).

70 75 Similar abutments may be provided respectively to engage the tail 39 of the feeder 15 and also the tail 40 of the locking plate 18, and in order to simplify the illustration as much as possible the abutments 37 and 38 shown on the drawings 75 may be taken as representative of any such abut-

ment as may be necessary to actuate the feeder, the locking plate and the arms 35 and 36.

5 Mounted on the spindle 32 is also an arm 41 having formed in it a cam slot 42 in which is received a pin 43 secured to the slide 27. As the spindle 32 is rotated from the position shown in Figure 1 to that of Figure 4 it will be seen that the arm 41 will be swung and the cam slot 42 will force the pin 43 and the slide 27 towards the axis of the needle-cylinder. 10

15 The operation of the mechanism so far described is as follows:—When the feeder 15 is in the non-feeding or inoperative condition it will assume the position illustrated in chain-lines in Figure 2. It will be observed that a shoulder 44 20 15 on the feeder 15 has engaged beneath the locking plate 18 which has been turned by its spring 19 into this position of engagement and the feeder is held thereby out of action. At this time the slide 27 and the gripper 25 are in the full-line 25 positions illustrated in Figure 2. When it is desired to bring the feeder into operation an adjustable abutment such as 38 is controlled by the pattern mechanism to come into the path of the tail 40 of the locking plate 18 to swing the latter 30 against the tension of the spring 19 to disengage the shoulder 44 of the feeder 15. The feeder 15 is immediately moved into the full-line position shown in Figure 2 by the pressure of its control spring 45 which is a compression spring tending 35 at all times to force the feeder into the feeding position. During this movement the clamp 20 is held in rubbing contact with the nose of the gripper 25 and the resilience of the latter will permit sufficient movement thereof to allow the feeder 40 to swing into feeding position. During this movement of the feeder the gripper 25 still maintains a relatively strong pressure on the clamp 20 to hold the thread gripped between the clamp and the adjacent surface of the feeder, and the trailing end of the yarn 23 is thus introduced into the hook of a needle which has descended so far down its stitch-cam as to be near the knocking over point. This condition is illustrated in Figures 8 and 9. 45

45 As soon as one or more needles have actually taken into their hooks the trailing yarn end, say, for example, four needles as shown in Figure 10, another adjustable abutment such as 37 will be brought into engagement with the end of 50 arm 36 and as there will be relative rotation between the abutment and the arm about the axis of the needle-cylinder the arm will be rotated and in so doing will turn the spindle 32 through the medium of the gears 34 to advance the slide 55 27 from the position illustrated in Figure 1 to that illustrated in Figure 4. In the latter figure the abutment 37 is shown as just having engaged and cleared the arm 36 and by this movement of the arm the slide will have been moved 60 towards the axis of the cylinder so as to bring the gripper 25 into the chain-line position with its nose free from engagement with the clamp 20. The yarn can now run freely through the feeder and will be taken by the needles in the usual 65 manner.

When the yarn is to be withdrawn another abutment such as 38 will be moved into a position to engage above the tail end 39 of the feeder 15 to swing it in a clockwise direction in Figure 70 2 away from the axis of the needle-cylinder. At the end of this swinging movement the locking plate 18 will automatically engage over the shoulder 44 and almost immediately thereafter an abutment 37 is brought into the path of the arm 75

35 to engage it, thereby swinging the arms 35 and 36 back to the position illustrated in Figure 1. This returns the slide 27 and the gripper 25 away from the axis of the needle-cylinder and brings 8 the overhanging nose of the gripper into contact with the clamp 20 to arrest the free run of the yarn through the feeder. In consequence a 10 breaking stress will be imposed upon the yarn and it will snap close to the surface of the knitted fabric in the manner already described in the prior specification previously referred to.

The movement of abutments such as 37 and 38 into their operative positions in timed relation to the relative travel past them of the parts with 15 which they are designed to engage is a matter well understood by those skilled in the art and can be effected by pattern controlling mechanism such as is usually provided in knitting machines of this character.

20 In the modified construction in Figures 5 to 7 the form and arrangement of the feeder 15, slide 27 and gripper 25 is similar to that already described with the exception that on the outer end of the slide 27 there are now two depending cams 25 46 and 47 having a shape clearly indicated in Figure 5.

Instead of the spindles 32, 33, arm 41, cam slot 42 and pin 43 for operating the slide the following mechanism is now employed. Mounted in the ring 11 behind the slide is a three armed lever pivotally mounted upon a pin 48. The three arms are indicated by the reference numerals 49, 50 and 51 of which the arm 50 enters the slot between the cams 46 and 47 and is shaped to co-operate with the cam faces again as clearly shown in Figure 5. The arm 49 has a cam face 151 at its end to be engaged by a pattern controlled abutment such as 152 that can be moved into and out from the path of the cam when the feeder is to be put into operation. In using the mechanism just described the feeder 15 is swung from its non-feeding to feeding position in the manner described in connection with Figures 1 to 4 and after 45 the required number of needles have taken the yarn from the feeder the gripper 25 is released by swinging the arm 50 from the position shown in Figure 7 in a clockwise direction as viewed in that figure or upwardly as viewed in Figure 5. The effect of this is to force the slide 27 forwardly towards the axis of the machine and thus to move the gripper 25 to the chain-line position to free it from engagement with the clamp 20. Movement of the arm 50 is brought about by 50 engagement of the cam face 151 by the abutment 152.

When it is again desired to bring the gripper back into engagement with the yarn clamp 20 another adjustable abutment, or the same abutment 152 adjusted to the requisite position, is brought into engagement beneath a pin 52 at the end of the arm 51. The abutment 152 is formed with a cam surface which as it passes the pin will raise the latter and return the arm 50 to the position illustrated in Figure 7.

It will be appreciated that the invention is applicable to a circular knitting machine in which either the cylinder or the cam-box is rotatable. 70 When the cylinder is rotatable the pattern controlled abutments such as 37, 38 and 52 will rotate with the cylinder and the yarn-feeder will remain stationary. When the cylinder is stationary the abutments will also be stationary except for their

movements of adjustment and the feeder will be rotated around the cylinder.

By suitable modification well understood by those who are versed in the art of knitting machinery the invention is equally applicable to flat bed knitting machines, in which case generally the feeder will be reciprocated lengthwise of the needle bed and the adjustable abutments such as 37, 38 and 152 will be stationary relatively to the needle bed except for their movements of adjustment. 10

Although in the specific example described the gripper is shown as being held closed until four needles have received the yarn end, it is to be understood that this is an arbitrary number and 15 may be either less or more as may be found most desirable in practice.

Moreover, it is to be understood that the invention is not limited to the precise details of construction described herein in connection with either of the two specific forms of the mechanism 20 which are given by way of example only.

We claim:

1. Yarn feeding mechanism comprising in combination a yarn feeder movable into and out from a yarn feeding position, a yarn gripper associated therewith to grip the yarn at such a position as to leave a free trailing end thereof extending from the feeder prior to the actuation of the feeder into a yarn feeding position, and means 30 to release the gripper only when the free end of yarn presented by the yarn feeder to the needles has been taken by at least one needle.

2. Yarn feeding mechanism comprising in combination a yarn feeder movable into and out from a yarn feeding position, a yarn gripper associated and movable in company therewith to grip the yarn at such a position as to leave a free trailing yarn end extending from the feeder prior to actuation of the feeder into the yarn feeding position, and means to release the gripper only when the free end of yarn presented by the yarn feeder to the needles has been taken by at least one needle. 40

3. Yarn feeding mechanism according to claim 1 in which the gripper-actuating mechanism comprises a slide by which the gripper is moved, a cam associated with the slide and a rocking arm to engage and operate the cam and one or more adjustable abutments to rock the arm. 50

4. Yarn feeding mechanism according to claim 1 in which there is interposed between the gripper and the feeder a yielding yarn clamp which is yieldingly urged at all times towards the body of the feeder to grip the yarn between the latter and the clamp in its passage to the needles and to subject the yarn continuously to a predetermined restraint to its free travel. 55

5. Yarn feeding mechanism comprising in combination a pivoted yarn feeder movable into and out from a yarn feeding position, a sliding yarn gripper having a portion overhanging a surface of the feeder over which the running yarn will pass in its passage to the feed point of the feeder, means to swing the feeder about its pivot into and out from the yarn feeding position, means to slide the gripper so as to move it towards and away from the feeder, the gripper being so positioned as to clamp the yarn so as to leave a free trailing yarn and extending from the feeder at all 70 times. 60

6. Yarn feeding mechanism comprising in combination a pivoted yarn feeder having a feed point at one extremity and a tail at the other extremity, a sliding yarn gripper having a portion over- 75

hanging a surface of the feeder over which the running yarn will pass in its passage to the feed point, means to engage the tail of the feeder to swing the latter about its pivot into and out from the yarn feeding position, means to slide the gripper so as to move it towards and away from the feeder, the gripper being so positioned as to clamp

the yarn so as to leave a free trailing yarn end extending from the feeder at all times.

7. Yarn feeding mechanism according to claim 6 having a yielding yarn clamp interposed between the gripper and the yarn.

HENRY HAROLD HOLMES.

ROBERT HAROLD ROBINSON.
